UNITED STATES PATENT OFFICE.

DONALD MACADIE, OF LONDON, ENGLAND, ASSIGNOR TO THE AUTOMATIC COIL WINDER & ELECTRICAL EQUIPMENT COMPANY LIMITED, OF LONDON, ENGLAND, A BRITISH COMPANY.

TRAVERSER MECHANISM FOR COIL-WINDING MACHINES.

Original application filed January 16, 1923, Serial No. 613,019. Divided and this application filed October 22, 1925. Serial No. 64,142.

To all whom it may concern:

Be it known that I, DONALD MACADIE, subject of George V, King of Great Britain and Ireland, residing at 109 Bowes Road, 5 Palmer's Green, London, N. 13, England, have invented new and useful Improvements in Traverser Mechanism for Coil-Winding Machines, of which the following is a specification.

10 This application is a division of my co-pending application 613,019, filed Jan. 16, 1923, for a coil winding machine which automatically stops working when a predetermined length of wire corresponding to a 15 given resistance has been wound on the bobbin and in which means are provided to vary the speed of reciprocation of the traverser arm relatively to the speed of rotation of the bobbin to be wound so that different thickness of wire can be wound with 20 their convolutions close together. The object of this invention is to provide improved traverser mechanism by means of which the length of the layers wound on the bobbin 25 may be accurately controlled and the said layers wound close up to the cheeks of the bobbin.

In the drawings,

30 Figure 1 is a front elevation of the major part of a coil-winding machine having embodied therein the improved traverser mechanism according to this invention, and

Figure 2 is substantially a plan of the same.

35 Figure 3 is a transverse section of the coil-winding machine and shows the mechanism for leading the wire to the bobbin to be wound and for reversing the motion of the traverser arm.

40 Figure 4 is a front elevation on an enlarged scale of the mechanism for reciprocating the traverser arm, and

Figure 5 is a transverse section of such mechanism.

45 Referring to the drawings and dealing first with the general construction of the machine, *a* is the base-plate, *b* is the motor for rotating the bobbin to be wound, *c* is an adjustable tail-stock for supporting one end of the bobbin, *d*, *d*, are end standards secured to the base and supporting a rotatable leading screw *d* for reciprocating the traverser arm which causes the wire to

travel along the bobbin while it is being wound on the latter. *b* is a driving disc secured on the motor spindle and arranged to drive, through the medium of a rubber-shod wheel *e*, a driven disc or follower *d* which is fast on the leading-screw *d*. This variable drive between the motor and the leading-screw forms the subject matter of my co-pending application Serial No. 613,019. The bobbin to be wound (not shown) is supported between the chuck *b* of the motor and the centre *c* of the tail-stock.

Referring now to the construction of the traverser mechanism, mounted on a rotatable guide rod *h* are two adjustable sliding stops *k*¹ and *k*² provided with forwardly projecting arms *k*³ and *k*⁴ respectively, (the right-hand arm *k*⁴ having been omitted in Figure 2 for the sake of clearness). The downwardly directed extremities of the arms are set in close engagement with the inner faces of the cheeks of the bobbin and the stops *k*¹ and *k*² are then secured firmly to the guide rod *h* by means of clamping nuts *k*⁵ and *k*⁶. The arms are now turned upwards and backwards so as to be out of the way of the traverser arm.

Mounted to slide, by means of a sleeve *k*⁷ on a fixed guide rod *k*⁸, and also on the rotatable rod *h* are two small posts *k*⁹ and *k*¹⁰ and a cam *k*¹¹ in the form of a double inclined plane. *k*¹² is a pin which can slide horizontally in the posts *k*⁹ and *k*¹⁰ and is provided with an arm *k*¹³ of which the portion *k*¹⁴ is undercut on opposite sides so as to form a cam consisting of a double inclined plane with its apex pointing downwards. The two cams are kept in close sliding engagement with one another by means of a tension spring *k*¹⁵ connected at its ends to the arm *k*¹³ and a stationary pin *k*¹⁶ respectively.

The cam *k*¹¹ which is somewhat stirrup-shaped at its lower end, is pivoted on the pin *k*¹⁶ and also has fixed thereto a double arm *k*¹⁷.

The double arm *k*¹⁷ is provided at its ends with half-nuts *k*¹⁸ and *k*¹⁹ respectively. The leading-screw is provided with two screw-threads of opposite hand with which the two said half-nuts respectively and alternately engage.

As the leading-screw rotates it causes the

half-nut which is in engagement therewith to move along the corresponding thread and at the same time carries the sleeve k^7 etc., along with it. Assuming that the posts k^9 5 and k^{10} are caused by the leading-screw to move to the right, the pin k^{12} will presently come into engagement with the left-hand end of the stop k^2 , with the result that the pressure thereby set up causes the pin k^{12} with 10 its arm k^{13} to become displaced endways thereby causing its other end to project beyond the post k^9 . During this movement the cam k^{14} becomes forced over the apex of the cam k^{11} against the resistance of the 15 spring k^{15} and, in so doing, rocks the double arm k^{17} about its pivot k^{16} thereby releasing the half-nut which was in engagement with the leading-screw and depressing the other half-nut into engagement with the leading- 20 screw.

The sleeve k^7 is now caused to move in the opposite direction until the pin k^{18} engages the right-hand end of the stationary stop k^1 whereupon the pin k^{12} and the double-arm 25 k^{17} are caused to return to their former positions by reason of the cam k^{14} passing back over the cam k^{11} . These operations are repeated until the bobbin is fully wound.

By setting the downward extensions of 30 the arms k^3 and k^4 hard up to the bobbin cheeks the windings can be brought close up to such cheeks. The inner ends of the stops k^1 and k^2 are provided with adjustable nuts k^{20} to allow for easy original adjustment of 35 the machine and to compensate for wear.

The wire is led to the bobbin between a pair of thin steel plates k^{21} carried by the traverser arm k^2 which, by means of its rearwardly extending limbs k^{22*} is pivoted 40 on the sleeve k^7 . These limbs can, by means of a screw k^{22**} , be adjusted to any desired degree of tightness against the shoulder k^{7*} (Figure 4). The sleeve k^7 is adjusted to work slidingly on the rod k^8 without shake 45 by means of nuts k^{7**} screwed on to its split ends. The traverser arm rests on a somewhat U-shaped trailer k^{23} the underside of the limbs of which are recessed so that said limbs can rest loosely on and be readily 50 lifted free of the rod k^8 . The trailer k^{23} has an arm k^{24} the underside of the nose of which is provided with a pad k^{25} which rests on the coil. One of the limbs of the trailer is extended rearwardly and is provided with 55 a counterpoise k^{26} which can be adjusted in position so that the pad k^{25} bears lightly on the coil. Thus, the traverser arm k^{22} can move backwards and forwards on the trailer k^{23} and is at the same time caused to rise as 60 the coil increases in diameter, by reason of the pad k^{25} resting on the coil. The trailer is caused to trail by reason of the nuts k^{7**} at opposite ends of the sleeve k^7 alternately 65 engaging the limbs of the trailer as the traverser arm reciprocates. When the latter re-

verses, the trailer remains stationary until the arm k^{22} has moved to its other side, that is, until the nut k^{7**} at the advancing end of the sleeve k^7 engages the adjacent limb of the trailer. At this period the trailer 70 also commences to reverse. Thus, at all positions of the traverser arm, the pad k^{25} remains in contact with a substantial number of turns of the last-wound portion of the bobbin. The pad k^{25} also serves to prevent 75 uncoiling of the winding should an accidental break occur in the wire, and the machine stops.

In order to enable both of the half-nuts to be freed from the leading-screw so as to 80 permit the traverser arm to be moved sideways freely and set to the desired position, the rearward extremities of the limbs k^{22**} are each provided with an eccentric surface, as shown at k^{22***} in Figure 3. Thus, when 85 the traverser arm is swung up into about the vertical position, the eccentric surfaces press on the double arm k^{17} on opposite sides of the centre k^{16} and, as they are made of similar shape or throw, they act in antagonism to the spring k^{15} and centralize the cam k^{11} thereby bringing the double arm k^{17} to the horizontal position and holding the half-nuts clear of the leading-screw.

I claim:

1. In a coil winding machine, a guide rod, adjustable sliding stops on said guide rod, projecting arms on said sliding stops having downwardly directed extremities adapted to be set in close engagement with the inner faces of the cheeks of the bobbin to be wound, traverser mechanism and means in operative engagement with said traverser mechanism adapted to engage the said sliding stops to reverse the said traverser 100 mechanism.

2. In a coil winding machine, traverser mechanism characterized by a slideable carriage having pivoted thereon the traverser arm and also having pivoted thereon a bracket the upper portion of which is in the form of a double inclined plane constituting a tilting cam and the lower portion of which has secured thereon a double arm carrying half-nuts at its ends, a screwed shaft, adapted to be alternately engaged by said half-nuts, a pin longitudinally movable in the bracket and carrying a double inclined plane adapted to co-operate with said cam, a guide rod, two adjustable sliding stops on said guide rod, projecting arms on said sliding stops having downwardly directed extremities adapted to be set in close engagement with the inner faces of the cheeks of the bobbin to be wound, the arrangement being such that the alternate engagement of the ends of the said pin with the said stops causes the double inclined plane on the said pin to move from one side to the other of the tilting cam and thereby cause the double arm to 110 120 125 130

rock so as to engage one half-nut with and dis-engage the other half-nut from the screwed shaft.

3. In a coil winding machine, traverser mechanism characterized by a slideable carriage having pivoted thereon the traverser arm and also having pivoted thereon a bracket the upper portion of which is in the form of a double inclined plane constituting a tilting cam and the lower portion of which has secured thereon a double arm carrying half-nuts at its ends, a screwed shaft adapted to be alternately engaged by said half-nuts, a pin longitudinally movable in the bracket and carrying a double inclined plane adapted to co-operate with said cam, a guide rod, two adjustable sliding stops on said guide rod, projecting arms on said sliding stops having downwardly directed extremities adapted to be set in close engagement with the inner faces of the cheeks of the bobbin to be wound, the arrangement being such that the alternate engagement of the ends of the said pin with the said stops, causes the double inclined plane on the said pin to move from one side to the other of the tilting cam and thereby cause the double arm to rock so as to engage one half-nut with and dis-engage the other half-nut from the screwed shaft, a trailer combined with said traverser mechanism and having a nose adapted to bear on the wire in process of being wound on the bobbin, and means to cause said trailer to lag behind the traverser arm.

4. In a coil winding machine, traverser mechanism characterized by a slideable carriage having pivoted thereon the traverser arm and also having pivoted thereon a bracket the upper portion of which is in the form of a double inclined plane constituting a tilting cam and the lower portion of which has secured thereon a double arm carrying half-nuts at its ends, a screwed shaft, adapted to be alternately engaged by said half-nuts, a pin longitudinally movable in the bracket and carrying a double inclined plane adapted to co-operate with said cam, a guide rod, two adjustable sliding stops on said guide rod, projecting arms on said sliding stops having downwardly directed extremities adapted to be set in close

engagement with the inner faces of the cheeks of the bobbin to be wound, the arrangement being such that the alternate engagement of the ends of the said pin with the said stops causes the double inclined plane on the said pin to move from one side to the other of the tilting cam and thereby cause the double arm to rock so as to engage one half-nut with and dis-engage the other half-nut from the screwed shaft, and cam surfaces on said traverser arm which can be brought into engagement with the double arm for the purpose of freeing the half-nuts from the screwed shaft.

5. In a coil winding machine, traverser mechanism characterized by a slideable carriage having pivoted thereon the traverser arm and also having pivoted thereon a bracket the upper portion of which is in the form of a double inclined plane constituting a tilting cam and the lower portion of which has secured thereon a double arm carrying half-nuts at its ends, a screwed shaft adapted to be alternately engaged by said half-nuts, a pin longitudinally movable in the bracket and carrying a double inclined plane adapted to co-operate with said cam, a guide rod, two adjustable sliding stops on said guide rod, projecting arms on said sliding stops having downwardly directed extremities adapted to be set in close engagement with the inner faces of the cheeks of the bobbin to be wound, the arrangement being such that the alternate engagement of the ends of the said pin with the said stops causes the double inclined plane on the said pin to move from one side to the other of the tilting cam and thereby cause the double arm to rock so as to engage one half-nut with and dis-engage the other half-nut from the screwed shaft, a trailer combined with said traverser mechanism and having a nose adapted to bear on the wire in process of being wound on the bobbin, means to cause said trailer to lag behind the traverser arm, and cam surfaces on said traverser arm which can be brought into engagement with the double arm for the purpose of freeing the half-nuts from the screwed shaft.

In testimony whereof I have signed my name to this specification.

DONALD MACADIE.
